US0D1112809S

(12) **United States Design Patent** (10) **Patent No.:** **US D1,112,809 S**
(45) **Date of Patent:** **** Feb. 10, 2026**

(54) **SAMPLE ANALYZER**

- (71) Applicant: **Canon Medical Diagnostics Corporation**, Tokyo (JP)
- (72) Inventors: **Kaori Umezawa**, Tokyo (JP); **Hiromasa Narumi**, Hamamatsu (JP)
- (73) Assignee: **Canon Medical Diagnostics Corporation**, Tokyo (JP)
- (**) Term: **15 Years**

(21) Appl. No.: **35/524,099**

(22) Filed: **Feb. 21, 2024**

(80) **Hague Agreement Data**

Int. Filing Date: **Feb. 21, 2024**
Int. Reg. No.: **DM/236362**
Int. Reg. Date: **Feb. 21, 2024**
Int. Reg. Pub. Date: **Feb. 21, 2025**

(30) **Foreign Application Priority Data**

Aug. 25, 2023 (JP) ..... 2023-017155 D
(51) **LOC (15) Cl.** **24-02**
(52) **U.S. Cl.**
USPC **D24/216**

(57) **CLAIM**

The ornamental design for a sample analyzer as shown and described.

DESCRIPTION

The patent or application file contains at least one drawing executed in color. Copies of this patent or patent application publication with color drawing(s) will be provided by the Office upon request and payment of the necessary fee.

1. Sample analyzer

1.1 : Perspective

1.2 : Front

1.3 : Back

1.4 : Right

1.5 : Left

1.6 : Top

1.7 : Bottom

1.8 : Perspective

1.9 : Reference perspective view

The design relates to an analyzer of feces sampled by a medical examination; The reproduction 1.8 is the perspective view.

(Continued)

tive view of the sample analyzer with the cover open; In the reproduction 1.9, the portion highlighted in blue color is translucent.

**1 Claim, 9 Drawing Sheets
(1 of 9 Drawing Sheet(s) Filed in Color)**
